UNITED STATES PATENT OFFICE

ARTHUR W. SCHMIDT, OF SPRING VALLEY, NEW YORK

RUBBER STAMP AND METHOD OF MAKING THE SAME

Application filed March 7, 1932. Serial No. 597,379.

This invention relates to rubber stamps and the method of making the same, an object of the invention being to provide a rubber stamp in which the cushion or body of the stamp consists of rubber which is vulcanized within the holder and projects beyond the holder for the attachment of a stamp facing strip containing type or other impressing indicia.

Another object of the invention is to provide a method of making rubber stamps consisting of providing a channel-shaped holder and then locating a block of a size appreciably smaller than the interior area of the holder in the holder and vulcanizing the rubber portion of the stamp in the holder.

The stamp includes preferably a channel-shaped metal holder in which crude rubber is located and vulcanized, the rubber filling the holder and projecting beyond the open face thereof, and preferably anchored in the holder by means of inturned flanges at the edges of the holder.

A stamp of this kind has many advantages in that it not only provides a superior cushion for the stamp face and gives a superior resilient action to the stamping operation, but it lengthens the life of the face of the stamp and insures a superior action in all respects.

Heretofore rubber stamps have ordinarily been made with blocks constituting backings to which the face of the stamp is secured, and the cushioning of the stamp face consists solely in the thickness of the strip constituting the stamp face, whereas with my improved stamp the entire body supporting the face is of rubber which is sufficiently soft and resilient for the purpose intended.

With these and other objects in view, the invention consists in certain novel features of construction and combinations and arrangements of parts, all of which will be more fully hereinafter described and pointed out in the claims.

In the accompanying drawing—

Figure 1 is a view mainly in longitudinal section but partly in elevation illustrating my improved rubber stamp; and

Figure 2 is a view in transverse section on the line 2—2 of Figure 1.

1 represents a channel-shaped holder which is preferably of metal, and 2 represents the body of the stamp which is of crude rubber vulcanized in the holder and, of course, adhearing to the surface of the holder by reason of the vulcanizing operation which takes place after the rubber is in the holder.

To prevent any possibility of the separation of the holder and body after the stamp has been used for a certain length of time which might tend to break the bond between the body and holder, I provide inwardly projecting flanges 3—3 at the edges of the holder, which not only project inwardly but backwardly; in other words, these flanges are at a slight angle, as clearly illustrated in Figure 2, so that they form a secure anchorage for the body.

The body 2 of rubber extends appreciably beyond the open edge of the holder, and a facing strip 4 is secured thereto in any approved manner and carries type or other printing indicia 5.

6 represents a handle which is secured to the stamp preferably by providing a shank 7 on the handle projecting through an opening 8 in the back of the holder 1, and secured in a recess 9 in a block 10 located in the holder and enclosed by the rubber body 2.

My improved stamp is, of course, capable of a wide range of modification in shape and form, as well as size and ornamentation, and I do not wish to be limited to the specific form of device illustrated but consider myself at liberty to make such changes and alterations as fairly fall within the scope of the claims. In constructing my stamp I first form the channel-shaped holder, then place the block 10 in the holder, insert the handle 6, the shank 7 on the handle being projected into the recess 9 in the block through the opening 8. The rubber portion 2 is then vulcanized in the holder.

What I claim is:

1. As a new article of manufacture, a rubber stamp comprising a channel-shaped holder, a block in the holder, a handle, a stud on the handle projecting through the back

of the holder and secured in the block, a rubber body filling the holder, enclosing the block and projecting beyond the holder.

2. As a new article of manufacture a rubber stamp comprising a channel-shaped holder, a block located in the intermediate portion of the holder and appreciably smaller than the interior of the holder, a rubber body filling the holder, enclosing the block and projecting beyond the holder, and a handle secured to the holder.

3. The herein described method of making rubber stamps including, first, providing a channel-shaped holder, then locating a block in the holder, said block being appreciably smaller than the interior area of the holder, then locating a body of rubber in the holder, and vulcanizing the rubber in the holder. 70
